CORN SAVING DEVICE

Albert Rode, Fort Jennings, Ohio

Application October 17, 1935, Serial No. 45,493

2 Claims. (Cl. 56—320)

This invention relates to a device for saving corn.

The primary object of the present invention is the attachment of a member to the frame of a corn binder, which drags along the ground in front of the drive wheel and deflects loose ears of corn lying on the ground from the path of the drive wheel, thereby preventing the destruction of the ears of corn.

10 Further objects of the invention are to provide a device of the character referred to that is strong, compact and durable, thoroughly reliable for its intended purpose, adaptable for attachment to all conventional corn binders, that is very easy to adjust and to manipulate, and that is comparatively inexpensive to manufacture and install.

20 With the foregoing and other objects in view, the invention consists of a novel construction, combination and arrangement of parts, as will be hereinafter more specifically described and illustrated in the accompanying drawings, wherein it is disclosed an embodiment of the invention, but it is to be understood that changes, variations, and 25 modifications may be resorted to without departing from the spirit of the claims hereunto appended.

25 In the drawings, wherein like reference characters denote corresponding parts through the several views:—

30 Figure 1 is a fragmentary top plan view of a corn binder, showing an adaptation therewith of a device in accordance with the present invention.

35 Figure 2 is a longitudinal vertical section taken substantially on line 2—2 of Figure 1, and looking in the direction of the arrows.

Figure 3 is a top plan view of the deflecting member detached from the binder.

40 Figure 4 is a vertical section taken substantially on the plane of line 4—4 of Figure 1, looking in the direction of the arrows and having parts removed.

45 Referring to the drawings in detail, A indicates the substantially rectangular frame of a binder, having forward and rear end rails 6, 7, respectively, and opposite side rails 8, 9 joined thereto. From the rear inner corner of the frame A extends a rightangular extension 10. One end of a 50 drive shaft and supporting axle 11 is journaled, as at 12, to an intermediate portion of the side rail 8. An intermediate portion of the drive shaft 11 is journaled, as at 13, to an intermediate portion of the side rail 9. The other 55 end of the drive shaft 11 is journaled, as at 14,

to the extension 10 and the grain wheel 15 is carried by an end of the drive shaft that projects through the extension 10. Between the grain wheel 15 and the rail 9 of the frame is the stalk elevating mechanism, indicated generally at 16, 52 and the stalks of corn pass between the elevating mechanism as the winder is pulled along. A tongue 17 is connected with the forward outer corner of the frame A and has a diagonal brace 18 connecting an intermediate portion thereof 10 with the forward inner corner of the frame A.

55 A relatively wide ground engaging drive wheel 19 is fixed to the drive shaft 11 between the side rails 8, 9. This drive wheel follows a path parallel with the standing stalks of corn. It sometimes happens that ears of corn fall from or are knocked off the standing stalks and as the binder moves along, the drive wheel passes over the ears of corn lying on the ground and destroys them. I construct an angular-shaped plate, indicated 20 at B, to drag along the ground in front of the drive wheel to deflect ears of corn free of the path of the drive wheel. The legs 20 and 21 of the angular member form an obtuse angle. The apex of the angle is directed forwardly and the 25 legs diverge rearwardly. The plate B is disposed edgewise so that the lower edges drag along the surface of the ground indicated at 22. On the leading face of the leg 20 of the angular member B is a pair of spaced ears 23, 24, and 30 these ears are located adjacent the outer ends. There is a pair of aperture spaced ears 25, 26 on the leading face of the leg 21, adjacent the outer free ends thereof. The lower end of a connecting link 27 is pivoted between the ears 23, 24, as at 35 28, and the lower end of link 29 is likewise pivoted between the ears 25, 26. The links 27, 29 incline upwardly from the ears, and are connected to the forward end rail 6 by the brackets 27^a and 29^a. Each bracket is formed in the same 40 manner, and a description of one will clearly teach the construction of the other. For the purpose of illustration, the bracket 27^a will be described.

45 The bracket 27^a consists of a U-shaped lower section 30 which underlaps the rail 6 of the frame. This U-shaped member 30 has opposite extensions 31, 32, which are bolted, as at 33, to the end of a bar 34 which clamps over the upper edge of the rail 6, thereby holding the U-shaped member 50 30 in clamped relation to the rail. A pair of spaced ears 35 are secured to the U-shaped member 30 and project rearwardly therefrom. The upper ends of the links 27 and 29 are pivoted, as at 36, between these ears. It will thus be seen, as 55

the binder is drawn along the links 27 and 29 pull the angular-shaped plate over the surface of the ground. To brace the legs 21, 22 of the angular-shaped plate B, there is a bar 37 which bridges the space between the legs. One end 38 of the bar 37 is secured to the trailing face of the leg 20, while the other end 39 of the bar 37 is secured to the trailing face of the leg 21. A lower end of the adjusting link 40 is pivoted as at 41^a 5 to the center of the bar 37, between upstanding apertured spaced ears 41, 42, which are fixed to the bar. The pivotal connection 41^a of the link 40 with the bar 37 is in alignment with the apex of the angular-shaped plate B.

10 There is a segmental-shaped plate having a flange 43 on the forward portion of the chord side 44 thereof, which is bolted, as at 45, to the forward rail 6 of the frame A. Between the arcuate portion 46 and the confronting edge of the chord side 44 there is an upstanding apertured lug 47. The outer edge of the arcuate side 46 of the plate has a series of spaced teeth 48 with pockets 48^a 15 between them to receive the spring pressed projectile detent 49 on one leg 50 of a bell crank lever, which is pivoted, as at 51, to the apertured lug 47. To the free end of the other leg 52 of the bell crank lever is pivoted, as at 53, the upper end of the link 40. When the detent 49 is disengaged, the bell crank lever may be rocked on the pivot 51, 20 thereby adjusting the angular-shaped plate B to raised or lowered position. When adjusted to the desired position, the detent 49, upon being re-

leased, engages between the teeth 48 and holds the member B in adjusted relation.

Having described my invention, what I claim is:

1. The combination with a corn binder including a frame, a drive shaft journaled to the frame, a ground engaging drive wheel fixed to the shaft, an angular-shaped plate disposed edgewise, a pair of spaced ears on the leading face of each leg of the plate, a pair of links pivotally connected at one end with the frame and at their other ends 5 to the ears, one for each leg, to drag the plate in the path of the drive wheel, a rod connected to the legs and bridging the angle between them, a segmental keeper plate carried by the frame having teeth on the arcuate portion, a bell crank lever 10 pivoted to the keeper plate and having a spring pressed detent selectively engageable with the teeth on the arcuate portion, a link pivoted at one end to an intermediate portion of the bar and at the other end to the bell crank lever for raising 15 and lowering said angular plate.

2. The combination with a corn binder including a frame, a drive shaft journaled to the frame, a ground engaging drive wheel fixed to the shaft, an angular member pivotally connected with the 20 frame to drag along the surface of the ground in front of the drive wheel to deflect ears of corn lying on the ground free of the path of the drive wheel, and means carried by the frame to adjust the member.

ALBERT RODE.
